DESIRÉ CRAYSSAC, OF LYON, FRANCE.

TWO-CYCLE VALVELESS INTERNAL-COMBUSTION ENGINE.

1,125,663.

Specification of Letters Patent. Patented Jan. 19, 1915.

Application filed February 27, 1913. Serial No. 751,669.

To all whom it may concern:

Be it known that I, DESIRÉ CRAYSSAC, citizen of the Republic of France, residing at Lyon, Department of Rhône, France, 5 have invented certain new and useful Improvements in Two-Cycle Valveless Internal-Combustion Engines, of which the following is a specification, reference being had therein to the accompanying drawing.

10 This invention has for its object to provide an improved valveless internal combustion motor working on the two-stroke cycle wherein a very high degree of expansion can be obtained and the cylinders are 15 filled effectually with a very pure explosive mixture, and wherein the fresh gases drive out the burnt gases without any stirring or mixing together of the two kinds of gases.

20 One of the characteristic features of this invention consists in the peculiar arrangement or construction of each motor element. This construction comprises the combination of two cylinders communicating with each 25 other at their upper parts and having their pistons connected to one and the same connecting rod. Further, in the said construction the admission of the explosive mixture takes place at the lower part of one of 30 the said cylinders when the corresponding piston is at the bottom of its stroke, while the exhaust takes place at the lower part of the other cylinder beginning a little before the admission into the first mentioned cylinder.

35 Another characteristic feature of this invention consists in the arrangement below the cylinders of each motor element, of a compressing cylinder, the piston of which is fixed to the connecting rod corresponding 40 to the said element and constitutes a guide for the two said pistons which are fixed to the bottom of this compressing piston. After these compressing cylinders 45 have drawn in the explosive mixture, the latter is driven out under pressure by them into the motor cylinders which are now at the period of admission.

With this object according to this invention a collecting and distributing device provided with passages or ports is provided for effecting in such a manner as to produce a regular operation of the motor, the passage 50 of the fresh gases driven by the compress-

ing pistons into the motor cylinders into which they are to be delivered.

This invention also comprises the provision of a rotary valve mounted on the crank shaft of the motor and designed so as to cause each of the compressing cylinders to communicate with the carburetor (supplying the explosive mixture), through the medium of the various ports of the collecting and distributing device above referred to,

60 One embodiment of the improvements of this invention is illustrated by way of example in the accompanying drawings, in which:

Figure 1 is an elevation of an apparatus 70 constructed in accordance with this invention; this apparatus comprising three motor elements, one of which (the one on the right-hand) is shown in section, half of the casing being assumed to be removed. Fig. 2 75 is a sectional elevation on the line II—II of Fig. 1. Fig. 3 is a section of one of the motor elements, on the line III—III of Fig. 2. Fig. 4 is a front elevation of the upper part of the device for collecting and distributing the explosive mixture. Figs. 5, 80 6 and 7 are three views in section of the collecting and distributing device, these sections being respectively on the lines V—V, VI—VI, and VII—VII of Fig. 4. Fig. 8 85 is an elevation of the special tubular member co-operating with a rotary valve, and into which open the various ports of the collecting and distributing device. Fig. 9 is a section on the line IX—IX of Fig. 8 of the 90 said tubular member.

The same references indicate the same elements in the various figures of the drawings.

In the example shown, M^1 , M^2 , M^3 , are the three motor elements to which there correspond respectively the three compressing cylinders C^1 , C^2 , C^3 .

1 is the motor shaft or crank shaft comprising in the example three cranks m^1 , m^2 , m^3 arranged at 120° apart on which are 100 mounted the connecting rods b^1 , b^2 , b^3 of the motor elements.

2 is the casing inside of which the shaft 1 rotates which is carried in suitable ball bearings 3, 4 in the usual manner.

5 is a fly wheel thereon.

Figs. 1, 2 and 3 illustrate the construction of the right-hand element of the apparatus

or group; this construction being the same for all the elements and is now to be described.

The interior of each of the motor cylinders is divided into two parallel cylinders 6, 7 communicating at their upper parts by means of a passage 8. In these cylinders there work respectively the pistons 9, 10. Each motor cylinder such as M^3 is prolonged in the form of a compressing cylinder such as C^3 in the interior of which works a piston 11 that is connected to the end of the connecting rod of the respective motor element. The pistons 9, 10 are fixed to the bottom of the piston 11 in such a manner that the compressing piston in its movement, forms the guide for the small pistons 9, 10 of the corresponding motor element. In practice, it is preferred to make the compressing cylinders C^1 , C^2 , C^3 of diameters slightly larger than twice the diameters of the cylinders 6, 7 of the corresponding motor element. The cylinder 6 is provided near its lower end with apertures 12 opening into a tubular member 13 which serves for the admission of the explosive mixture and communicates with one of the ports of the collecting and distributing device as hereinafter described. The cylinder 7 is provided near its lower end with apertures 14 opening into a tubular member 15 which serves for the exhaust of the burnt gases.

It is to be noted that as shown in the example, the piston 10 of the cylinder 7 uncovers the exhaust apertures 14 slightly before the admission apertures 12 are uncovered by the piston 9 of the cylinder 6. The object of this arrangement is hereinafter described.

16 is the collecting and distributing device for effecting a suitable communication between the compressing cylinders and the motor cylinders, and is connected to the carburetor through the medium of a special tubular member 17 and a rotary valve 18. The general arrangement of these elements is as follows: The gaseous mixture supplied by the carburetor is delivered into the tubular member 17 through a suitable duct suitably connected to the orifice 19 which communicates with a circular passage 20 provided in the interior of the tubular member 17. The latter has further three apertures a^1 , a^2 , a^3 which are arranged concentrically to the shaft 1 and communicate with suitable ducts c^1 , c^2 , c^3 that open respectively into the apertures d^1 , d^2 , d^3 of the ducts e^1 , e^2 , e^3 of the collecting and distributing device 16.

The rotary valve 18 is formed with a circular passage 21, the length of which is equal to about $\frac{1}{3}$ of the circumference of the slide. This passage thus places each of the

apertures a^1 , a^2 , a^3 successively in communication with the circular passage 20 that receives the explosive mixture.

The internal ducts or passages of the collecting and distributing device 16 are arranged as follows: The passage e^1 passes in front of the admission ports of the left-hand cylinder of the motor element M^1 with which it communicates through the openings f^1 ; then it passes around the passages e^2 , e^3 on its way to the admission ports of the compressing cylinders C^3 with which it communicates through the opening g^3 . The passage e^2 passes in front of the admission ports of the compressing cylinder C^1 with which it communicates through an opening g^1 , and thence it passes to the admission ports of the left-hand cylinder of the motor element M^2 with which it communicates through the opening f^2 . The passage e^3 passes in front of the admission ports of the compressing cylinder C^2 with which it communicates through the opening g^2 , and then it passes to the admission ports of the left-hand cylinder of the motor element M^3 with which it communicates through the opening f^3 .

The arrows h^1 , h^2 , h^3 indicate the several paths traversed by the explosive mixture through the various passages of the collecting and distributing device 16. This arrangement enables the fresh gases to be forced into the motor elements M^1 , M^2 , M^3 respectively by means of the compressing cylinders C^3 , C^1 , C^2 .

The operation of the improved apparatus is as follows: When the rotary valve 18 occupies the position shown in the drawings, it places the carburetor in communication with the passage e^2 and consequently with the passage e^2 of the collecting and distributing device. At this moment the piston of the compressing cylinder C^1 is making its downstroke (the shaft 1 being assumed to rotate in a direction of the arrow i in Fig. 2) so that the cylinder of this compressor is filled with fresh gas. On the other hand the admission ports 12 of the cylinder 6 of the motor element M^2 are closed by the corresponding piston 9 as shown in Fig. 2.

When the piston of the compressor C^1 is about to commence its up stroke, it will compress the explosive mixture because at this moment the rotary valve 18 has shut off communication between the passage e^2 and the carburetor. This compression is effected in the said passage and in the cylinder C^1 until the moment when the piston 9 of the motor element M^2 uncovers the corresponding admission ports 12, namely, when the said piston reaches the bottom end of its stroke. The fresh gases are thus compressed through the cylinders 6 and 7

5 during the whole time that the ports 12 remain open, that is to say, while the crank m^2 is traversing the lower arc α of its course, and the compressing piston C^1 continues to drive the gases into the cylinders of the element M^1 , while the crank m^1 is traversing the arc β of its course (Fig. 2). The same operation is repeated for each of the motor groups of the improved motor apparatus, and need not be more fully described herein.

10 From Fig. 1 it will be clearly seen that the exhaust ports 14 of the cylinder 7 of each element are uncovered by the corresponding piston 10 a little time before the admission ports 12 of the cylinder 6 of this said element are uncovered by the piston 9. The result of this arrangement is that at the moment when the compressing piston of the cylinder C^2 , for instance is about to compress the fresh gases into the cylinders of the motor element M^2 , there is already produced in the cylinders 6 and 7 of the said element an expulsion of the burnt gases in 15 the sense indicated by the arrow j in Fig. 1. Consequently the expulsion of the burnt gases and the filling of the motor cylinders with fresh gases must take place with certainty, and when the two pistons 9 and 10 20 of each motor element move upward simultaneously, they will compress fresh pure gases which are not mixed with the residues of burnt gases, for the purpose of providing explosive mixture at the moment of the explosion.

25 What I claim is:—

1. A valveless internal combustion motor working on the two stroke cycle constituted by means of a plurality of combined elements 30 comprising respectively a motor cylinder divided into two parallel cylindrical chambers, a piston movable in each of said chambers, admission ports and exhaust ports located respectively in the lower parts of the cylindrical chambers of the motor cylinder, a passage located at the upper part of said cylinder for establishing free communication between its two cylindrical chambers, a compressing cylinder located below the 35 double-chambered motor cylinder, a piston movable in the said compressing cylinder upon which are fixed the two pistons of the motor cylinder superposed on it, a motor shaft having as many cranks as the motor includes compressing cylinders; connecting rods respectively articulated at their lower end on the corresponding crank of the motor shaft, and at their upper end on the piston of the compressing cylinder 40 to the said crank, a carbureter supplying the explosive mixture to the motor, suitable conduits insuring, on the one hand, the filling of the compressing cylinders with the explosive mixture supplied by the carbureter, and, on the other hand, the forcing 45 of the said mixture into the motor cylinders, corresponding respectively to the said compressing cylinders, and means for making and breaking at the proper times the communication between each of the compressing cylinders and the said carbureter.

50 on the other hand, the forcing of the said mixture into the motor cylinders, corresponding respectively to the said compressing cylinders, and means for establishing and breaking at the proper time the communication between each of the compressing cylinders and the said carbureter.

55 2. A valveless internal combustion motor working on the two stroke cycle, comprising a plurality of elements combined together, each comprising a motor cylinder divided into two parallel cylindrical chambers, a piston movable in each of said chambers, admission ports and exhaust ports located respectively at the lower parts of the two cylindrical chambers of the motor cylinder, 60 the conformation of said ports and said pistons being such that the exhaust ports are uncovered at the end of the stroke of the corresponding piston a little before the conjugated piston uncovers the admission ports, a passage located at the upper part of said cylinder establishing a free communication between the two cylindrical chambers of 65 said cylinder, a compressing cylinder located below the double chambered motor cylinder, 70 a piston movable in the said compressing cylinder upon which are fixed the two pistons of the motor cylinder superposed thereon; a motor shaft having as many cranks as the motor includes compressing cylinders; connecting rods respectively articulated at their lower end on the corresponding crank of the motor shaft, and at their upper end on the piston of the compressing cylinder 75 corresponding to the said crank, a carbureter supplying explosive mixture to the motor, suitable conduits insuring, on the one hand, the filling of the compressing cylinders with the explosive mixture supplied by the carbureter, and, on the other hand, the forcing 80 of the said mixture into the motor cylinders, corresponding respectively to the said compressing cylinders, and means for making and breaking at the proper times the communication between each of the compressing cylinders and the said carbureter.

85 3. A valveless internal combustion motor working on the two stroke cycle, consisting of the combination of a plurality of conjugated elements comprising respectively a motor cylinder divided into two parallel cylindrical chambers, a piston movable in each of said chambers, admission ports and exhaust ports located respectively in the lower parts of the two cylindrical chambers of the motor cylinder, a passage located at the upper part of said cylinder establishing free communication 90 between the two cylindrical chambers thereof, a compressing cylinder located below the double chambered motor cylinder, a piston movable in the said compressing cylinder upon which are fixed the two pistons of the motor cylinder superposed thereon, a 95

motor shaft having as many cranks as the motor includes compressing cylinders; connecting rods respectively articulated at their lower end on the corresponding crank of the motor shaft, and at their upper end on the piston of the compressing cylinder corresponding to the said crank, a carbureter supplying explosive mixture to the motor, a collecting and distributing device comprising internal passages connecting the admission ports for the explosive mixture in each of the motor cylinders to the ports of the corresponding compressing cylinder, a tubular member comprising as many internal passages as there are passages in said collecting and distributing device, and means for placing successively at the proper times each of the passages of said tubular member in communication with said carbureter.

20 4. A valveless internal combustion motor working on the two stroke cycle, consisting of the combination of a plurality of elements comprising respectively a motor cylinder divided into two parallel cylindrical chambers, a piston movable in each of said chambers, admission ports and exhaust ports located respectively in the lower parts of the two cylindrical chambers of the motor cylinder, a passage located in the upper part of said cylinder establishing free communication between the two cylindrical chambers therein, a compressing cylinder located below the double chambered motor cylinder, a piston movable in said compressing cylinder upon which are fixed the two pistons of the motor cylinder superposed thereon, jointed at one end to one of the cranks of the motor shaft and at its other end to the piston of the compressing cylinder corresponding to said cranks, a carbureter supplying explosive mixture to the motor, a collecting and distributing device comprising internal passages connecting the admission orifices for the explosive mixture in each of the motor cylinders, to the suction and delivery orifices of the corresponding compressing cylinder, a tubular member comprising as many internal passages as there are passages in said collecting and distributing device, a circular passage in the interior of said tubular member in constant communication with the duct supplying explosive mixture from said carbureter, a rotary valve mounted on the motor shaft comprising a partly circular passage corresponding to the circular passage of said tubular member, apertures formed in the said tubular member communicating respectively with each of the ducts corresponding with the internal passages of said collecting and distributing device located in

the path followed by said partly circular passage of the rotary valve, whereby each of said passages is placed successively at the proper time in communication with the said carbureter.

5. A valveless internal combustion motor working on the two stroke cycle, comprising the combination of a plurality of conjugated elements comprising respectively a motor cylinder divided into two parallel cylindrical chambers, a piston movable in each of said chambers, admission ports and exhaust ports located respectively in the lower parts of the two cylindrical chambers of the motor cylinder, a passage located in the upper part of said cylinder establishing free communication between the two cylindrical chambers therein, a compressing cylinder located below the double chambered motor cylinder, a piston movable in said compressing cylinder upon which are fixed the two pistons of the motor cylinder superposed thereon, jointed at one end to one of the cranks of the motor shaft and at its other end to the piston of the compressing cylinder corresponding to said cranks, a carbureter supplying explosive mixture to the motor, a collecting and distributing device comprising internal passages connecting the admission orifices for the explosive mixture in each of the motor cylinders, to the suction and delivery orifices of the corresponding compressing cylinder, a tubular member comprising as many internal passages as there are passages in said collecting and distributing device, a circular passage in the interior of said tubular member in constant communication with the duct supplying explosive mixture from said carbureter, a rotary valve mounted on the motor shaft comprising a partly circular passage corresponding to the circular passage of said tubular member, apertures formed in the said tubular member communicating respectively with each of the ducts corresponding with the internal passages of said collecting and distributing device located in the path followed by said partly circular passage of the rotary valve, the various elements constituting the motor being arranged relatively to one another and combined with one another in such a manner that the admission of the fresh explosive mixture is effected in each of the compressing cylinders by the suction produced by the downstroke of the corresponding piston at the moment when the rotary valve mounted on the motor shaft establishes communication by means of the distributing tubular member between said carbureter and the passage of the collecting and distributing device corresponding to the last mentioned compressing cylinder, while the said rotary valve shuts off this communication during
